A. WIGGINS.

WINDING MECHANISM FOR MOVING PICTURE MACHINES.
APPLICATION FILED DEC. 11, 1909.

980,378.

Patented Jan. 3, 1911.

Fig. 1.

UNITED STATES PATENT OFFICE.

ALFRED WIGGINS, OF EAST LEXINGTON, MASSACHUSETTS.

WINDING MECHANISM FOR MOVING-PICTURE MACHINES.

980,378.

Specification of Letters Patent.

Patented Jan. 3, 1911.

Application filed December 11, 1909. Serial No. 532,528.

To all whom it may concern:

Be it known that I, ALFRED WIGGINS, a citizen of the United States, and resident of East Lexington, in the county of Middlesex and State of Massachusetts, have invented an Improvement in Winding Mechanism for Moving-Picture Machines, of which the following description, in connection with the accompanying drawings, is a specification, like letters on the drawings representing like parts.

In using the film of moving-picture machines, two results are desirable, among others, first to avoid frictional contact with the body portion or picture surface of the film, and second to facilitate the rapid and convenient travel and transfer of the film from the delivery end of the machine to the receiving end, and vice versa. My present invention aims to secure these results to the best advantage.

I provide means whereby the film is maintained in edge engagement wherever it slides or tends to slide or move frictionally over an adjacent surface, as distinguished from being permitted to engage said surface between said edges or at the picture portion of area of the film.

I also provide a connection between the delivery end of the machine and the film-receiving end of the machine for positively driving the former from the latter at a predetermined decreased ratio of movement, whereby the film is permitted to feed forward through the machine without any possibility of being subjected to longitudinal strain or other tension tending to warp or distort the film.

My invention also includes a reel which coöperates with the aforesaid mechanism in facilitating the edge engagement of the film in unwinding and the quick transfer of the film from the receiving end to the delivery end of the machine without rewinding.

Further advantages will be more fully apparent in the course of the following description, taken in connection with the accompanying drawings, in which I have shown a preferred embodiment of the invention.

In the drawings, Figure 1 represents in side elevation and partly in section the complete machine; Fig. 2 is a view thereof in front elevation, the upper portion being in section and partly broken away; Fig. 3 is a view in top plan, partially broken away,

showing a portion of the delivery mechanism; Fig. 4 is a view in side elevation of the receiving reel, looking at the side opposite that shown in Fig. 1; Fig. 5 is a central longitudinal section of said reel taken on line 5—5, Fig. 6; and Figs. 6 and 7 are central transverse sectional views of the two separable parts of the reel taken on the line 6—6, Fig. 5.

As my invention is applicable to any usual kind of lantern and moving-picture mechanism, I have merely indicated the same herein in a general conventional manner at 1, 2, 3 mounted on a platform 4. At the upper end 60 of said platform is a support 5 preferably hinged at 6 to the main portion of the machine and provided with a film-holder 7 mounted on a central axis 8 provided with a beveled gear 9 driven by a beveled pinion 10 on a shaft 11 provided with a spur pinion 12 in mesh with a gear 13 rotated by a flexible shaft 14 which passes downwardly through an eye 15 on a bracket 16 to the lower part of the machine in position to receive a film-receiving reel 17. The latter reel and said shaft are driven by a smooth-grooved pulley 18 and slip belt 19 in usual manner in connection with the moving-picture mechanism 2, which is operated by a 70 handle 20. The film-holder 7 is shaped like a pan or circular tray for receiving a head-portion 21 of the reel, which constitutes one of the leading features of my invention. Accordingly I will describe this reel in detail at this point for the better understanding of the entire invention. The reel comprises two opposite sides or heads 21, 22, the former provided with a central conical hub 23 and a plurality of slots or elongated 80 openings 24, and the head or side 22 is provided with a hub 25 having a central conical recess 26 into which the hub 23 fits when the two parts are put together to constitute a complete reel. In the hub 25 are mounted a 90 series of rods 27 corresponding in number to the slots 24 and each provided with an out-turned clamping end 28 adapted to enter said slots when turned in line therewith, whereupon they are given a quarter turn into 100 the position indicated in Fig. 4, thereby locking the two sides or heads of the reel together. Each locking rod 27 is provided at its opposite end with a handle 29 whereby it may be conveniently turned, said handle preferably standing in the same direction as the hooked end 28 so as to indicate when the 110

parts are properly locked together. Secured at proper distances apart around the periphery of the hub 25 are spring members 30 corresponding in number to the rods 27, and co-operating with one of these springs 30 is a clamping spring 31.

Alined openings 32, 33, 34 are provided for receiving a holding spindle 35 when in position to receive the film 36. Each locking rod 27 is also provided with a cam portion 37. When the reel parts are clamped together as a whole, the locking rods 27 are turned to locking position, as shown best in Figs. 4, 5, and 6. The end of the film 36 is then tucked in between the spring 31 and the adjacent spring 30, which, under the action of the out-turned cam portion 37, hold it sufficiently against slipping for the winding operation. Thereupon the reel 17 is rotated in usual manner by the slip belt 19 and pulley 18, being wound tightly upon the hub 25 the same as usual with reels in general. Having filled the reel with the entire ribbon of film 36, the sides of the reel are unclamped from each other by turning the handles 29 of the rods 27 from their clamped position as shown in the drawings, into recesses 38 provided therefor in the wall of the hub 25. This permits the springs 30 and the spring 31 to move inwardly against the hub 25 out of holding engagement with the inner portion of the film, which is thereby released so that the side 22 of the reel and its hub 25 and all the parts carried thereby may be lifted from the film without any danger of injuring the latter, leaving said film supported in proper winding position on the side or head 21 of the reel. Said side or head 21 of the reel, with its load of coiled film, is thereupon transferred to the pan or holder 7 as shown in Figs. 1, 2, and 3. The inner end of the film is then threaded through a polished metal ring 39, oval in shape, as clearly shown in Figs. 1 and 2, at the end of an overhanging rod 40 which is pivotally supported in a post 41. To lock said ring and arm in normal central position, the rod is provided with a depending lug 42 occupying a notch 43 in said post. This holds the arm and ring in operative position when desired, and yet permits it to be raised from said notch and swung to one side when it is desired to put a new film in place in the holder 7. The leading end of the film is then pulled through the ring 39 and out between usual guide rollers 44 provided in a usual cover or box 45 provided to protect the film within the box from fire in case the exposed outer portion thereof should catch fire.

The box is provided with a hinged portion 46 at one side to permit the reel head 21 and its load of film to be put in place within the box. A guide roller 47 is also preferably provided for directing the film to the picture

machine, and an adjustable brace 48 serves to regulate the angle of the support 5 so that it may be maintained horizontal. Because of the cone shape of the hub 23, only the lower edge of the film tends to engage the same, and the elliptical or oval ring 39 also prevents the body of the film from touching it. The ring restricts the film to an edge engagement therewith, and these are the only parts of my apparatus over which the film must slide, so that the picture portion of the film is kept from being scratched or injured. As before mentioned, an important feature of my invention resides in driving the holder 7 at a slightly decreased speed over that of the receiving reel. The proportion of the gears which I have found preferable is to provide the gear 9 with forty seven cogs, the gear 10 with fourteen cogs, the gear 12 with twelve cogs, and the gear 13 with forty cogs. I have found this decreased speed of delivery over the winding speed just sufficient to prevent any possibility of strain being brought upon the ribbon of film by the positive pull of the biograph mechanism 2 and the gradually increasing size of the turns of film being received and delivered, so that as a result the film has much longer life than if said delivery mechanism were not run at said increased speed. The coil of film in the film-holder 7 necessarily loosens toward the center more or less, and this is desirable and is promoted by my mechanism, as thereby the successive turns of the film have less tendency to rub on each other as the film is delivered from the center of the coil, whereas the coil of film on the receiving reel is held taut and hence as snug as possible all the time it is being wound, and the differential in the speed of the winding device and the speed of the delivery device just compensates for this difference in the condition of the two coils and promotes the desired looseness of the upper coil.

Having described my invention, what I claim as new and desire to secure by Letters Patent is:

1. The herein described film-handling mechanism for a moving-picture machine, comprising a rotary device for delivering the film, a rotary device for receiving the film so delivered, and driving connections between said two devices, including means for positively driving the rotary delivering device at a slightly slower speed than the winding device.

2. The herein described film-handling mechanism for a moving-picture machine, comprising a rotary device for delivering the film, a rotary device for receiving the film so delivered, a flexible rotary driving shaft, and positive gear connections between said two devices, geared to drive the delivery device slightly slower than the receiving device.

3. In a machine of the kind described, film delivery mechanism, including a relatively stationary delivery ring through which the film is delivered, whereby the film is maintained in edge contact only and is saved from being scratched or injured between its edges.
4. In a machine of the kind described, film-delivery mechanism, including a film-supporting portion having a conical shaped hub for aiding in maintaining the body of the film against frictional injury.
5. In a machine of the kind described, film-delivery mechanism, including a pan shaped holder, and a conical shaped hub for aiding in maintaining the body of the film against frictional injury.
6. In a machine of the kind described, film-delivery mechanism, including a pan shaped holder, a conical shaped hub for aiding in maintaining the body of the film against frictional injury, and means for rotating said holder at a slight decrement slower than the film is being withdrawn.
7. In a machine of the kind described, a film-receiving reel comprising separable sides, including between them an expansible hub, and means for contracting said hub when the hub is to be removed from the film.
8. In a machine of the kind described, a film-receiving reel comprising separable sides, including between them an expansible hub, and means for contracting said hub when the hub is to be removed from the film, including a peripheral spring support for the inner coil of the film.
9. In a machine of the kind described, a film-receiving reel comprising separable sides, including between them an expansible hub, and means for contracting said hub when the hub is to be removed from the film, including a peripheral spring support for the inner coil of the film, and including a peripheral spring support for the inner coil of the film, and cam mechanism for expanding and contracting said spring support.
10. In a machine of the kind described, a film-receiving reel comprising separable sides, including between them an expansible hub, and means for contracting said hub when the hub is to be removed from the film, including a peripheral spring support for the inner coil of the film, and a locking rod mounted transversely in said hub, and provided with means adjacent one end for removably locking the sides together, and with an intermediate cam portion for expanding said spring support when the reel sides are locked together.
11. In a machine of the kind described, a reel comprising separable sides provided respectively with central hub portions, one of which is conical and fits within the other, and the latter provided with a contractible periphery externally contractible when within the roll of film for facilitating the separation therefrom of the film when wound thereon.

In testimony whereof, I have signed my name to this specification, in the presence of two subscribing witnesses.

ALFRED WIGGINS.
